UNITED STATES PATENT OFFICE

TRUMAN C. NARAMORE AND CLYDE JUDSON BARNWELL, OF LOS ANGELES,
CALIFORNIA.

CIGARETTE-SMOKER'S POUCH.

982,292.

Specification of Letters Patent. Patented Jan. 24, 1911.

Application filed May 27, 1908. Serial No. 435,354.

To all whom it may concern:

Be it known that we, TRUMAN C. NARAMORE and CLYDE JUDSON BARNWELL, both citizens of the United States, residing at 5 Los Angeles, in the county of Los Angeles and State of California, have invented a new and useful Cigarette-Smoker's Pouch, of which the following is a specification.

An object of this invention is to provide a 10 novel convenience for cigarette smokers who make a practice of rolling their own cigarettes immediately before smoking the same.

Another object of the invention is to provide for cigarette smokers a pouch that will 15 preserve the tobacco from pulverization to which it is subjected when carried in the pocket in an ordinary tobacco sack.

The invention may be embodied in various forms, and we do not limit the invention to 20 any specific form of construction.

The invention includes a pouch in which provision is made for carrying cigarette papers as well as the tobacco and it also includes a novel form of pouch for carrying 25 tobacco and enabling the smoker to open the pouch and pour the tobacco into the paper with great ease and facility.

The invention may be applied in various forms and we do not limit it to any specific 30 construction.

The accompanying drawings illustrate the invention in the two forms we at present deem most desirable.

Figure 1 is a view of the front side of the 35 form of pouch which is constructed to carry both the tobacco and the cigarette papers. In this view the pouch is shown closed. Fig. 2 is a view of the same pouch as it appears when open for pouring out tobacco. Fig. 3 40 is a view of said holder open for filling with tobacco. A portion of the loop 9 is broken away to show the position the flap or strap 7 takes inside the loop 9 when the pouch is thus open. Fig. 4 is a section on line x⁴, Fig. 45 1. Fig. 5 is a section on line indicated by x⁵, Fig. 4, showing the front and back portions of the pouch. The back of the pouch appears at the right and the front of the pouch at the left of the view, and in relation thereto as though turned over to the left from the back of the pouch, a portion of the wall which separates the paper pocket from the tobacco receptacle is broken to expose the 50 reinforcing metal strip and a portion of the paper pocket. Fig. 6 is a view showing the

several blanks which may be employed in constructing the form of pouch shown in the preceding views. Fig. 7 is a section on line corresponding to x¹, Fig. 1, showing the pouch as constructed without a paper-holding pocket. 60

The pouch comprises a body 1 provided with a cavity 2 forming a tobacco receptacle and a pocket 3 for cigarette papers. An opening or mouth 4 is provided at one end 65 of the pouch body extending from edge to edge of said body for the purpose of filling the pouch with tobacco.

5 is a lip extending part way across the pouch alongside said opening 4, and preferably terminating short of the other edge 70 of the pouch to form an opening 6 through which the tobacco may be readily poured when the parts of the pouch are in the position shown in Fig. 2.

7 designates a flap forming an extension of the back wall 8 of the pouch and extending over the openings 4 and 6 to close the same. 75

9 designates a loop secured to the flap and 80 extending around the body of the pouch and adapted to slide therealong to close the orifice or opening 10 that is provided in the front wall 11 of the pouch to give access to the cigarette paper pocket 3 when the loop 85 is slipped along the body a sufficient distance from the open end of the pouch.

12 designates a slit or slot in one edge wall of the pouch to allow a package of cigarette papers to be inserted into such pocket. It 90 is understood that the papers may be inserted through the orifice 10 so that it is not necessary in order to use the pocket 3 that the edge slit or slot 12 be provided.

Preferably, the cigarette paper pocket 3 95 is arranged at the end of the pouch opposite the tobacco opening 4 so that when the loop 9 has been slid along the body 1 of the pouch to give access to the orifice 10, the flap 7 will have been withdrawn from the open end 100 of the pouch to allow tobacco to be poured from the pouch, and when the loop is drawn down to cover the orifice 10 the flap 7 is brought into position to close the openings 4 and 6. 105

The pouch may be constructed of any desired and convenient number of pieces within the judgment of the manufacturer.

In the form shown in Figs. 1 to 6 inclusive, 13 designates a frame which may be 110

stamped from thick leather or other suitable material, the same being provided with two partially inclosed spaces 14 and 15 respectively provided with openings 6 and 12. 5 The space 15 is of sufficient size to accommodate a package of cigarette papers, and the gap 12 is of sufficient dimensions to allow such package to be inserted into the open space 15. 16 designates a sheet of leather or 10 other material fastened to the inner face of the frame 3 to form the bottom of the cigarette paper pocket 10. 17 designates a U-shaped frame fastened to the frame 13 to give additional thickness to the pouch, and 15 forming with said frame 13 the edge walls of the tobacco receptacle. 18 is a finishing band or strip cemented to the outer sides of the frames 13 and 17. This band or strip is shown in perspective in Fig. 6. The other 20 parts are shown in plan in said figure. 19 designates tongues that are adapted to finish the ends of the edge walls of the frame. It is to be understood that each of the several parts may be cut of a single piece or may be 25 built up in the ordinary course of manufacture out of two or more pieces, and that only the general outlines of the parts are shown, no attempt being made to illustrate the parts as being formed of pieces fastened together. 30 20 designates a reinforcement of sheet metal or other suitable material to bridge over the orifice 12 to prevent the front wall 11 from sagging across said orifice. Projections at 19, 19, on opposite ends of the mouth opening 4, 6, of the pouch hold the flap against shifting edgewise.

In practice, to fill the cigarette paper pocket the user will simply slip the loop 9 along the body from the position shown in 40 Fig. 1 to that shown in Fig. 2, until the orifice 12 is uncovered. Thereupon the package of cigarette papers may be inserted through the orifice 12 into the pocket 3; or in case the orifice 12 has not been provided 45 the package of papers may be slipped into place through the orifice 10. When the parts are in this position which is shown in Fig. 2, the pouch is sufficiently open to allow tobacco to be poured therefrom so that the 50 user may, with his thumb or finger, remove the outermost cigarette paper, and may immediately proceed to fill the same with tobacco from the pouch without any further manipulation of the pouch. When the cigarette paper has been filled, the loop may 55 be returned to the position shown in Fig. 1, thus at the same time closing the tobacco receptacle and the cigarette paper pocket. To fill the pouch with tobacco, the loop 9 may 60 be slipped entirely off of the pouch body, as shown in Fig. 3, thus making all of the openings 4 and 6 accessible for filling. When the pouch has been filled, the loop may be returned to the position shown successively in

Figs. 2 and 1. By providing a flat-walled pouch with a pocket just inside one wall to contain the cigarette papers, a single appliance is made convenient for carrying both the tobacco and the cigarette papers in proper condition for instant use. 70

We claim:

1. A pouch comprising a flat body provided with a receptacle that is open at one end only, a flap forming an end-extension of one side wall of the body and adapted to 75 fold over said end extension to close the same, and a loop the width of which is less than the length of the body, said loop being fastened to the flap and adapted to slide along the body, a length of flap being provided between the loop and the side wall sufficient to accommodate the loop when the same is slid off of the body to open the pouch so that when the pouch is open the flap may hold the loop at the mouth of the receptacle ready to be slid over the body to close the pouch. 80

2. A pouch comprising a flat body having a receptacle that is open only at one end of the body, a flap forming an extension of a side wall of the body to close the open end of the receptacle, the body being provided at the end opposite the open end of the receptacle with a pocket having an orifice in the side wall of the body and a slot through an 90 edge wall of the body, and a loop on the flap adapted to slide along the body, said loop being of sufficient width to close the orifice and the slot when the flap is adjusted to close the mouth of the receptacle, the flap 95 being of sufficient length between the loop and the mouth of the receptacle to accommodate the loop when the loop is slid off of the body and thereby to hold the loop in position at the mouth of the receptacle ready to 100 be slid back onto the body. 105

3. A pouch provided with an opening at one side and having projections at the ends of the opening, a strap forming an extension of one wall of the pouch and arranged to fit 110 between said extensions and over the opening, and means to hold the strap in position to close said opening.

4. A pouch comprising a frame and side walls, a gap being provided in the frame to form a slot, means to form a pocket in the frame adjacent the slot, and a reinforcing metallic strip on the frame to support the wall at the slot formed by said gap. 115

In testimony whereof, we have hereunto 120 set our hands at Los Angeles, California, this 20th day of May, 1908.
